Patented Jan. 5, 1915.

UNITED STATES PATENT OFFICE.

JOHN WOOLDRIDGE, OF ROCKDALE, TEXAS, ASSIGNOR OF FIFTY-ONE ONE-HUNDREDTHS
TO LEONARD ISAACS, OF ROCKDALE, TEXAS.

COTTON-GIN.

1,124,094.

Specification of Letters Patent.

Patented Jan. 5, 1915.

Application filed January 5, 1914. Serial No. 810,478.

To all whom it may concern:

Be it known that I, JOHN WOOLDRIDGE, a citizen of the United States, residing at Rockdale, in the county of Milam and State 5 of Texas, have invented a new and useful Cotton-Gin, of which the following is a specification.

The present invention appertains generally to cotton gins, and aims to provide 10 novel means for facilitating the ginning of the seed cotton.

It is the object of the present invention to provide unique means for facilitating the removal of the lint from the saw, whereby 15 the brush will be relieved of its duty to a considerable extent, thereby increasing the efficiency of the ginning action.

A further object of the present invention is to provide means whereby the air suction 20 may be employed for assisting in removing the lint from the saw, prior to and simultaneously with the removal of the lint by the brush.

It is also within the spirit of the invention 25 to provide means of the character indicated, which may readily be embodied in the prevailing or standard types of cotton gins, without necessitating any radical alterations or changes, and without entailing any 30 appreciable expense, the present invention being comparatively simple and inexpensive in construction, as well as simple, practical and efficient in its use.

With the foregoing general objects outlined, and with other objects in view, which will be apparent as the nature of the invention is better understood, the present invention resides in the combination and arrangement of parts and in the details of construction 35 on hereinafter described and claimed, it being understood that changes in the precise embodiment of the invention herein disclosed can be made within the scope of what is claimed without departing from the spirit 40 of the invention.

The invention has been illustrated in its preferred embodiment in the accompanying drawing, wherein the figure is a sectional view of an ordinary or prevailing type of 45 cotton gin, embodying the present improvements.

In the cotton gin as illustrated, a pair of multiple saws are employed, the upper saw being designated by the numeral 1, and the 50 lower saw by the numeral 1'. The usual

brushes 2 and 2' coöperate with the respective saws 1 and 1' for removing the lint from the saws. The gin also includes a lint flue 3 having the openings 4 and 4' leading to the spaces between the brushes 2 and 2' 55 and the underlying mote boards or concaves 5 and 5' respectively. The foregoing structure or arrangement is common in prevailing or standard types of cotton gins, and need not be described at length, it being understood that the several parts above described extend the entire length of the gin stand, as usual.

In carrying out the present invention, the brushes 2 and 2' are covered by the circular 70 "boxes" or hoods 6 and 6' respectively, which extend from the openings 4 and 4' respectively to a point directly adjoining the contacting portions of the respective co-operating saws and brushes. The hoods 6 75 and 6' fit snugly over the brushes, whereby the strength of the air currents through the coöperating portions of the saws and brushes is greatly increased.

The gin structure includes the boards 8 80 and 8' disposed adjoining the respective saws 1 and 1' with their free edges terminating short of the hoods 6 and 6' respectively, to provide openings 9 and 9' in advance of the coöperating or contacting portions of respective saws and brushes.

Valves or dividing boards 7 and 7' are hinged or pivoted to the free edges of the respective boards 8 and 8', and have their free edges projecting inwardly toward the 90 respective edges of the hoods 6 and 6', respectively, or toward the contacting portions of the respective brushes and saws.

The valves or dividing boards 7 and 8 may be adjusted or set at various positions, by 95 any well known means, which need not be described or illustrated in detail.

Particular attention is directed to the fact that there is an air passage between each of the boards 8 and 8', and the corresponding 100 saw, which air passage extends between the corresponding dividing board or valve and the corresponding saw to the contacting portions of the respective saw and brush. It is also to be observed that each hood projects 105 beyond the corresponding dividing board or valve, to a point directly adjacent the contacting portions of the corresponding brush and saw, the corresponding dividing board or valve being swingable to and from the 110

outer side of the hood, to control the air currents through the corresponding inlets 9 or 9', and the corresponding passage between the board 8 or 8' and the adjacent saw.

5 In operation the air will be drawn inwardly through the openings or slots 9 and 9' to and between the coöperating portions of the saws and brushes. The inlet or air through the openings or slots 9 and 9' may 10 be controlled by properly adjusting the valves or dividing boards 7 and 7', as will be obvious. It is also apparent that air will be drawn from over the saws, as in the present cotton gins, the course of the air being indicated by dot and dash arrows in the drawing, while the direction of rotation of the saws and brushes are indicated by full line arrows.

As a result of the admission of the currents of air through the openings or slots 9 and 9', and from over the tops of the saws, the currents or streams of air will converge or meet at the periphery of the saws directly in advance of the contacting portions of the 25 saws and brushes, whereby the air suction will greatly facilitate the loosening and removal of the lint from the saws. The eddies set up by the currents of air at the free edge of the valves or dividing boards 7 and 7' 30 will serve to loosen and release the lint from the saws, whereby the brushes 2 and 2' will be greatly relieved of the duty of removing the lint from the saws.

With the provision of the improvements 35 above described, the brushes in being relieved of a great portion of their duty, may be rotated much slower than usual, and furthermore, the suction at the forward or free edges of the mote boards or concaves 5 and 40 5' will be reduced, thereby reducing the tendency to draw the motes, dust and other extraneous matter back into the gin to be carried out with the lint. This also enables the brushes to be employed from throwing 45 the motes and extraneous matter away from the saws and over the edges of the mote boards, as indicated by the dotted line arrows.

It is evident that the valves or dividing 50 boards 7 and 7', as well as the openings or slots 9 and 9' extend the full length of the gin stand, or are coextensive with the saws and brushes, and if desired, the openings or

slots 9 and 9' may each be in the form of a series of apertures or slots, with the same 55 effect.

From the foregoing, the advantages of the present improvements will be obvious to those skilled in the art, it being observed that the objects aimed at have been carried out satisfactorily, whereby the ginning of the seed cotton will be facilitated, or whereby the lint will be readily and effectively removed from the saws. As a result, the character or quality of the cotton given off by 60 the gin will be superior to that given off by the ordinary gin.

Having thus described the invention, what is claimed as new is:

1. In a cotton gin, a saw, a brush coöperating therewith, a hood disposed snugly over the brush and projecting toward the contacting portions of the saw and brush, a board disposed adjoining the saw and terminating short of the said hood, there being an air passage between the said board and saw, and an air inlet between the said board and hood, and a valve hinged to the said board and projecting toward the contacting portions of the saw and brush to control the 70 air currents through the said passage and inlet.

2. In a cotton gin, a saw, a brush coöperating therewith, a hood disposed snugly over the brush and projecting toward the 75 contacting portions of the saw and brush, a board disposed adjoining the saw and terminating short of the said hood, there being an air passage between the said board and saw, and an air inlet between the said 80 board and brush, and a valve hinged to the said board and projecting toward the contacting portions of the saw and brush to control the air currents through the said 85 passage and inlet, the hood projecting beyond the valve to a point directly adjacent the contacting portions of the brush and saw, and the valve being swingable to and from the outer side of the hood.

In testimony that I claim the foregoing as 90 my own, I have hereto affixed my signature in the presence of two witnesses.

JOHN WOOLDRIDGE.

Witnesses:

B. W. BALDRIDGE,
S. G. HODGE.
